HOUSEHOLD ART LINK SERIES AND COMBINATIONS INCLUDING SAME

Emma M. Menge, Newton, Mass.

Application August 17, 1934, Serial No. 740,240

1. Claim. (Cl. 41—10)

This invention relates to art link series, mainly for use in series or sets for ornamentation in connection with numerous household articles, but adapted for ornamental use in other relations and to combinations involving the same.

In order that the principle of the invention and the general mode of use thereof may be clear, I have in the accompanying drawing, illustrated several ornamental shapes or forms of the ornamental art link series and one of the many uses to which the same may be put.

In the drawing:

Fig. 1 is a front elevation of an ornamental link of lozenge or diamond shape (being one of the series thereof), the hook portion being shown as integral or unitary with the ring-like portion of the structure;

Figs. 2, 3, 4 and 5 are front elevations of other ornamental forms or shapes of the art link series. Fig. 6 represents a portion of a window curtain or drapery wherein the art ornamental links are employed in a series or set in one use of my invention;

Fig. 7 is a side elevation of one of the brackets for supporting the curtain rod; and

Fig. 8 is a plan view of part of the curtain rod having an end portion of material or finish like that of the art link series.

The purpose of my invention is to provide so-called art link series that may be made in various sizes, shapes and colors, and of various materials lending themselves to ornamental effects, such as "bakelite", bottle ware, etc. The link series, according to their different sizes and shapes, may be employed in different ornamental relations in connection with household articles, wearing articles and novelties. I will mention a few only of the uses to which the said link series may be put and I have illustrated one use only thereof in Figs. 6 to 8.

The said link series are particularly adapted for ornamental use in connection with window curtains, portieres, draperies, etc. They may also be used ornamentally in connection with such articles relating to household furniture as lamp shades, bed spreads, table runners and the like. In such uses they may be employed in sets to connect different parts of the fabric or other structure, as, for example, in table runners. In connection with ornamentation of articles of wear, they may be used with caps, bonnets, shawls, belts, etc.

The purpose of my invention is to provide, as ornamental articles of manufacture to be sold in quantities or series and in various sizes, col-

ors and materials, the so-called art link series, which, when used as illustrated for example in Fig. 6, provide ornamental means for supporting window curtains, draperies and portieres, and which, when individually secured in series to articles of wear or articles associated with furniture, such, for example, as sofa pillows, produce an artistic effect.

The purpose of my invention is to make each link of the series as attractive and artistic in appearance as possible, and therefore I either make the same of some material such as "bakelite" of the desired color, or I may make the link of wood or celluloid and then color the same.

In Fig. 1, I have represented a link of the series at 4 as having at 5 a hook integral therewith. In Fig. 2, I have represented a link of the series as of heart shape; in Fig. 3, I have represented the link 7 as of a crescent shape; and in Fig. 4, I have represented the link 8 as of trefoil or clover shape. In Fig. 5, the link 9 is represented as of triangular shape, and the same is slotted or slit at 10 on a bevel or incline so as to permit the two meeting parts to be gently separated for the insertion of any desired article or part with which the link is used.

The links of the series may be of any suitable thickness, and in Fig. 6, I have represented two of the links 4 as of sufficient thickness to give enough strength for supporting the window curtain or portiere 11. Preferably the brackets 12 for supporting the curtain rod or portiere pole 13 are of the same material as the links. Desirably such pole is provided with removable ends 14 which are of the same material as the links and desirably of the same color, so that the same color scheme would be used throughout.

It is obvious that if the series of links be of small size, they may be used ornamentally when secured in different geometrical figures or designs to household articles, such, for example, as couch covers and lamp shades.

Obviously, if art link series, such as herein described, be provided for sale in numerous colors, sizes and shapes, numerous uses of the same will suggest themselves to purchasers, as they constitute an attractive article readily lending itself to household decoration.

Referring particularly to Fig. 6, wherein the window curtain or portiere is indicated, it will be noted that the upper portion at least thereof is of a lace or like construction having openings formed at intervals therein which are properly worked or otherwise protected from running or tearing. Such openings may occur at 55

numerous points in the edge of the curtain and through any of these the points of the hooks 5 may readily be inserted and as readily removed when the curtain or portiere is to be cleaned or for any other purpose. Thus, it will be seen that it is unnecessary to remove the curtain rod or pole 13 from its brackets 12. In other words, it is unnecessary to remove the links 4 from the pole 13 in order to permit the curtain or portiere 10 11 to be taken down. This is one obvious advantage of a use of the links and hooks herein disclosed.

Other uses of the links, or links and hooks, or links in the form of hooks, of my invention may 15 be made, and that illustrated in Fig. 6 is one instance only thereof.

I am, of course, aware that large cumbersome wooden rings have heretofore been provided to be strung or received on portiere poles, but such 20 articles were not attractive in appearance, they were cheaply made, and did not lend themselves to other ornamental or artistic uses, which is an important purpose of my invention.

A link with an attached hook of my invention 25 may be used in series wherever a hanging effect is desired, as in curtains, curtain pulls, scarf ends, etc. Such links may be made up in sets or series of various sizes preferably ranging from three 30 eighths of an inch, or even less, to two inches in width.

My invention includes the making of a series of 35 so-called art links with their hooks in graduated sizes, so that stores may have available the links and hooks, either separate or integral with each other, for various ornamental uses, for some of

which uses the largest size would be desired, and for others of which the smallest size would be employed, there being a substantial number of intermediate sizes for special uses.

Having thus described several illustrative embodiments of my invention, it is to be understood that although specific terms are employed, they are used in a generic and descriptive sense and not for purposes of limitation, the scope of the invention being set forth in the following claim. 5 10

A household art link as an article of manufacture particularly adapted to be used in a set or series for the ornamentation of appropriate household articles, such as portieres, draperies, etc., said art link being a unitary, rigid or non-bending structure, the opposite flat faces whereof are polished or reflecting, the said link being of substantial thickness having a ring-like portion, and providing an opening of relatively small diameter by which it may be strung upon a curtain support, or be attached to the article to be ornamented, said link having a hook-like extension of substantially the same thickness as the ring-like portion and therefore also presenting reflecting surfaces, the opening of the ring-like portion being 25 of merely sufficient diameter to permit the art link to be attached to the article which it ornaments in use, whereby a series or set of such art links may be used in cooperating relation or association to produce together an ornamental 30 effect, due to the association of a series of such links upon or with a single article of household use.
